(57) **CLAIM**

The ornamental design for a remote control, as shown.

DESCRIPTION

FIG. 1 is a front view of a remote control showing my design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken lines represent unclaimed subject matter.
